SMOKE BOX CASING FOR A LOCOMOTIVE

Harry C. Decker, Altoona, Pa., assignor to The Pennsylvania Railroad Company, Philadelphia, Pa., a corporation of Pennsylvania

Application July 17, 1936, Serial No. 91,156

3 Claims. (Cl. 105—2)

This invention relates to locomotives and particularly to features of their construction which reduce air resistance. In the streamlining of locomotives, the front of the usual smoke-box requires a casing of streamline design such as the "bullet nose". In order to avoid the expense and difficulties of introducing an entirely new type of smoke-box, it has become desirable to provide such a casing which will combine with and become structurally part of the usual type of smoke-box. The severe service demands upon railway structures further complicate the problem of how this is to be done safely. An insecure front casing would be serious in the case of a locomotive.

Therefore, one object of the invention is the provision of a streamlined smoke-box casing which combines with the usual smoke-box structurally to form a rugged and secure unit. Another object is the provision of such a casing which can be completely removed for repairs and allows routine access to the smoke-box proper. Other objects are concealment of securing fittings to reduce wind resistance and simplicity and economy of construction. Still further objects and advantages will become apparent from the following detailed description of one embodiment of the invention, reference being had to the accompanying drawings.

Fig. I of the drawings is a side view of the front portion of a locomotive equipped with the invention.

Fig. II is a front view of same.

Fig. III is a sectional view taken about the lines III—III of Fig. II.

Fig. IV is a sectional view taken about the lines IV—IV of Fig. III.

Fig. V is a sectional view taken about the lines V—V of Fig. III.

Fig. VI is a sectional view taken about the lines VI—VI of Figs. I and III.

Fig. VII is a fragmentary view of the hinge and joint between the casing and casing door of Fig. VI, showing details of construction.

Fig. VIII is a sectional view about the lines VIII—VIII of Fig. II.

Fig. IX is a sectional view about the lines IX—IX of Fig. IV.

Fig. X is a sectional view about the lines X—X of Fig. I, showing the interior of the smoke-box casing with access door removed.

Fig. XI is a sectional view about the lines XI—XI of Fig. I, showing the interior of the access door in the front of the smoke-box casing.

The specific embodiment of the invention

shown in the drawings may, for the purposes of a detailed description, be analyzed generally into a locomotive smoke-box 1 having a stack 2, and a hinged door 3, a body casing 4, a smoke-box casing 5 having an access door 6 with a head-light housing 7.

The smoke-box 1 is of a conventional type with the usual smoke-box door 3. Around the forward circular edge of the smoke-box 1 are welded a number of blocks 11 which are designed to hold the body casing 4 in place at its forward end, within which is welded a retaining ring 12. This ring 12 is recessed to form a shoulder 13 which engages the blocks 11 as shown in Fig. IX. The body casing 4 is part of an outer shell placed around the locomotive to lower the wind resistance and this body casing 4 is formed with smoke-box casing 5 according to principles of streamlining. The "bullet nose" shape of the casing 5 is designed to fit into the general streamline scheme both at its sides and at its bottom portion 14. A supporting shelf 42 is also provided to receive the bottom part of the casing 5, the shelf 42 being firmly fastened to the front part of the locomotive as shown.

The smoke-box casing 5 has a retaining ring 16 welded inside its rear edge. This retaining ring 16 is recessed to form a shoulder which cooperates in engagement with a similar shoulder formed on ring 12. These rings 12 and 16 are locked in engagement by dogs 17 attached to the front of the smoke-box 1. The dogs 17 are of a usual type and need not be described in detail. They consist of a bolt 20 held in place by a nut 21, a securing element 22 having a hole to receive the bolt 20, and a nut 19 for holding the element 22 in place. The smoke-box casing 5 is strengthened by interior ribs 23 which radiate from a strengthening ring 24 which forms the access door opening. The ring 24 is welded in place as are the ribs 23.

The access door 6 has a strengthening ring 25 welded in place and recessed to form a shoulder which cooperates in engagement with a similar shoulder formed on strengthening ring 24. The interiorly placed hinges 30 are important; exterior hinges would materially increase the wind resistance and impair the efficiency of the streamlining. These hinges 30 comprise brackets 31 and 32 attached respectively to rings 24 and 25, and pivotally joined arms 33 pivotally attached to the brackets 31 and 32. This hinge 30 allows the door 6 to be swung completely clear of the door opening and also permits seating adjustment as the door 6 is closed. A head-light housing 7 of

a usual type is placed in the center of the access door 6. The housing comprises a frame 36, a hinged bezel door 37 having glass face 38 and a fastening means 39 of a usual type. The access door 6 is also strengthened by ribs 41 on its inner face.

In order to relieve the strain on the hinges 30 by which the access door 6 is attached to the casing 5, a number of countersunk screws 40 are provided. These screws 40 normally hold the door 6 in place; the hinges 30 are useful in opening and shutting the door 6.

It is evident that the invention shows a simple and rugged means of providing a "bullet nose" for the front of a streamlined locomotive. The smooth outer surface is maintained and a strong structural unit is provided.

While the above description of one embodiment of the invention is in some detail, it will be obvious to one skilled in the art that various variations and changes may be made without departing from the spirit of the invention as hereinafter claimed.

Having thus described my invention, I claim:

25 1. In combination with a locomotive smoke-box partially covered by a body casing, a detachable smoke-box casing over the front of the smoke-box in continuation of the body casing, said casings being of a form to reduce wind resistance, 30 a retaining ring on the front edge of the body casing, blocks positioned around the front part of the smoke-box and secured thereto, said retaining ring having a shoulder for locking against said blocks, a retaining ring attached to the edge 35 of said smoke-box casing, said two retaining rings

being in abutting relation with cooperating positioning shoulders at the joint, dogs fastened to the smoke-box for holding said rings together, and an access door in said smoke-box casing having interiorly placed hinges, said door being further secured in place to said smoke-box casing by recessed screws and cooperating shoulders located at the joint and partially on the door and partially on the casing.

2. In combination with a locomotive smoke- 10 box, a detachable casing of a form having low wind resistance characteristics, means for securing the casing to the smoke-box, including a retaining ring secured around the casing edge, means attached to the smoke-box for abutting 15 contact with said ring and dogs attached to the smoke-box for holding said ring in said abutting contact, an interiorly hinged access door in said casing, and a head-light housing in said door.

3. In combination with a locomotive smoke- 20 box, a detachable casing of a form having low wind resistance characteristics, said casing having an access door opening formed therein, means for securing the casing to the smoke-box, an interiorly hinged access door in said casing comprising 25 brackets secured to said door and casing and having pivotally attached arms which are pivotally joined to each other, a strengthening ring attached to said casing around said access door opening, a second strengthening ring attached to said door around the edge thereof, said strengthening rings having cooperating shoulders formed thereon, and a head-light housing in said door.

HARRY C. DECKER. 35
